UNITED STATES PATENT OFFICE.

OTIS A. MYGATT, OF NEW YORK, N. Y.

DESIGN FOR A SHADE, REFLECTOR, OR SIMILAR ARTICLE.

No. 40,178.

Specification for Design.

Patented July 27, 1909.

Application filed June 5, 1908. Serial No. 436,987. Term of patent 14 years.

To all whom it may concern:

Be it known that I, OTIS A. MYGATT, a citizen of the United States, residing at New York, in the county of New York and State of New York, have invented a new, original, and ornamental Design for a Shade or Reflector or Similar Article, of which the following is a specification, reference being had to the accompanying drawing, forming part thereof.

The drawing is a side elevation of a shade or reflector embodying my design.

My design as shown is a shade having a body consisting of a substantially bell-shaped upper portion and a cylindrical

lower portion. The exterior of both portions of the shade is substantially covered with prisms lying in the planes of the axis of the shade. The appearance of a shade made according to my design is that of an ordinary prism glass reflector provided with pendent prisms.

I claim—

The ornamental design for a shade, reflector, or similar article, as shown and described.

OTIS A. MYGATT.
